CASE FOR CARTRIDGES

Oskar Alfred Östman, Tikkakoski, Kuikka,
FinlandApplication November 21, 1936, Serial No. 112,124
In Finland November 26, 1935

6 Claims. (Cl. 42—49)

Cartridge magazines with stationary cartridge carriers and comprising circular or spiral guides in which the cartridge rows are pushed to the opening by means of a spring actuated driver member 5 engaging the rearmost cartridge, the cartridges passing successively out of the said opening, are known. These cartridge magazines are deficient in that the friction to be overcome for advancing the cartridges in the stationary carrier is relatively great, so that a commensurately great spring power, which increases with the length of the row of cartridges, is necessary. This defect is avoided in known cartridge magazines wherein the cartridge carrier and the cartridges rotate together. However, these magazines are, in turn, again deficient in that, because of their limited dimensions, they can accommodate only a few cartridges. A well known magazine endeavors to overcome this defect by a concentric arrangement of two rotatable drums, each with a cartridge guide, i. e. arranging two separate cartridge guides in such manner that the two drums and the cartridge rows therein rotate consecutively. The arrangement of two drums, however, 25 makes the construction complicated and, by reason of the requirement for great space, not utilizable with all firearms.

The present invention is designed to solve, in a simple and inexpensive manner, the problem 30 of introducing a large number of cartridges into the magazine, while requiring only a slight spring power to move the cartridges. The cartridge magazine forming the subject of the present invention also comprises two separate cartridge 35 guides which are evacuated successively. However, according to the invention, the two cartridge guides are arranged in a single, common cartridge carrier which is rotatable about a central angle to the extent necessary to employ the 40 one cartridge guide and which is provided with a projection engaging behind the last cartridge of the row in this cartridge guide, and is actuated by a feeder member which is rotated by spring means and which bears against the last 45 cartridge of the row in the second cartridge guide, so that the first cartridge guide is evacuated indirectly by the feeder member by rotation of the cartridge carrier and then, after the latter comes to a standstill, the other cartridge 50 guide is evacuated directly by the feeder member which advances the row of cartridges in this guide.

On the drawing,—

Fig. 1 shows the case loaded, filled and 55 covered, seen from the bullet side, the bolt in

cross-section and part of the cover of the spring case cut away.

Fig. 2 shows a vertical section made through the middle of the case the cover side downwards. 5

Fig. 3 shows the case covered and the latch of the cover closed. The exterior of the case is formed by a short cylinder 1, the base 1^a of the cylinder and a cover 1^b which can be fastened to the cylinder in a way described below. 10

The cartridges are held in the case by means of the following gear.

On a loose round washer 2, which can revolve round the mainshaft 5, one or more plate cylinders are fastened, according to the drawing, two 15 plate cylinders 2^a and 2^b, in such a way that between the cylinder 1 and these plate cylinders are left two cartridge channels 3 and 4 where the cartridges are placed as the figure shows. The form of these channels will be described later. 20

The mainshaft 5 is secured to the base 1^a of the cylinder, and round this shaft there rotates also a spring case 6. This case and the washer 2 can rotate either at the same time or separately if required. 25

A spring 7 which is in the spring case 6, is at one end by means of a pin 8 secured to the mainshaft 5 and at the other end to the inner wall of the case 6.

To the outer wall of the spring case a cartridge 30 feeder 11 is pivoted about a peg 10.

In order to compress the spring 7 there are in the cover 12 projections 12^a by means of which the cover 12 and with it the spring case 6 can be made to rotate, and thus the spring can be 35 compressed.

In a hole in the middle of the mainshaft 5 there is a bolt 23 in such a position that it cannot rotate in the hole of the shaft, but it can move longitudinally. A spring 24 presses the bolt 23 40 against the cover 12.

On the inner surface of the head 9 of the bolt there are oblique cogs 23^a the corresponding holes 23^b of which are in the cover 12.

When the spring 7 is compressed, the cogs 23^a 45 rise up from their holes 23^b and sink therein again when the compressing is stopped.

The bolt 23 has also another function. When the cover 1^b of the case has been placed in position, the end 23^c of the bolt is pressed inwards 50 with some suitable object e. g. the end of a cartridge, and then the head 9 of the bolt rises up and is thus loosened from the cover 12 of the spring case.

In the cover 1^b of the case there is a pin 1^c 55

round which turns a bolt 1^d . This bolt is pushed under the head 9 , and then a hook in the end of it comes under the head of a pin 1^e in the cover 12 .

5 On the outer surface of the bolt 1^d there is a projection 36 , which, when the bolt is pushed in, is pressed behind one of the cogs 23^a . In this way the cover 12 is locked and the cartridge feeder 11 can press the row of cartridges for 10 ward.

In Fig. 1 the cartridge channels 3 and 4 are filled with cartridges. Below an outlet 37 in the wall of the cylinder 1 there is a cartridge lifter 29 shaped like a fork. When the cartridges are 15 gliding against it, they rise up into the outlet.

The outer cartridge channel 3 is, as mentioned above, formed by the wall of the cylinder 1 and by the plate cylinder 2^a , the washer 2 acting as the base of the channel. The one end of the 20 plate cylinder 2^a almost touches the wall of the cylinder 1 , the other ending at the projection 30 . This projection has been made so wide that it just fits in between the arms of the cartridge lifter 29 .

25 When the cartridge feeding has proceeded so far that the channel 3 is empty, the projection 30 has been pressed between the arms of the cartridge lifter 29 ; and the mouth of the channel 4 has come to the outlet 37 .

30 Behind the fork 29 there is a shoulder 31 the purpose of which is to stop the projection 30 when it has gone past the cartridge lifter 29 . In this way is also the end 2^c of the plate cylinder 2^a prevented from revolving forward.

35 When filling the case, remove the cover 1^b of the case in such a way that the end 23^c of the bolt is pressed inwards and then the cog 23^a in the head 9 of the bolt goes past the projection 36 in the latch 1^d . Now the latch 1^d can be 40 turned away. When the latch 1^d is opened, the cover of the case can be lifted off and the spring 24 presses the head 9 of the bolt against the cover 12 of the spring case 6 .

After this the spring of the case is 45 compressed by seizing with the fingertips the projections 12^a and turning to the left as far as possible.

After this the case is filled in such a way that the cartridges are put into the cartridge channels 3 and 4 with their bases against the washer 2 , 50 after which the cover of the case is closed in the way described above, and the case is ready for firing.

When firing the spring 7 makes the spring 55 case 6 and at the same time the washer 2 rotate by means of the feeder 11 and the cartridges of the cartridge channel 4 . When the cartridges, as described, go through the outlet 37 , the washer 2 rotates under the influence of the spring 7 until 60 the cartridges in the channel 3 are all gone, and the projection 30 comes against the shoulder 31 (the case is now acting as a drum case) and the shoulder 31 has such a position that the end of the channel 4 comes to the outlet 37 . When the 65 washer 2 can no longer rotate but the spring 7 is pressing the cartridges with the feeder 11 , the cartridges in the channel 4 go off through the outlet 37 in the same manner as in the rod cases.

I claim:

70 1. A cartridge case of the character described comprising a substantially cylindrical housing including a peripheral wall, a washer arranged for rotation within said housing, spaced relatively inner and outer substantially annular partition members in said housing, said partition members

being operatively associated with said washer so as to rotate therewith, said washer and partition member defining a pair of juxtaposed relatively inner and outer channels adapted to receive the cartridges and from which, consecutively, the 5 latter are discharged, the wall of said cylindrical housing being provided with an outlet for said cartridges, means on the inner surface of said wall for directing cartridges to said outlet, means for evacuating one of said channels by rotating 10 said washer and associated partition members, and means for holding said washer and partition members against rotation upon completion of the evacuation of said one channel, said evacuating means then functioning also to evacuate the other 15 of said channels while said washer and partition members are held against rotation.

2. A cartridge case of the character described comprising a substantially cylindrical housing including a peripheral wall, a washer arranged for 20 rotation within said housing, spaced relatively inner and outer substantially annular partition members in said housing, said partition members being operatively associated with said washer so as to rotate therewith, said washer and partition 25 members defining a pair of juxtaposed relatively inner and outer channels adapted to receive the cartridges and from which, consecutively, the latter are discharged, the wall of said cylindrical housing being provided with an outlet for said 30 cartridges, means on the inner surface of said wall for directing cartridges to said outlet, means for evacuating one of said channels by rotating said washer and associated partition members, means for holding said washer and partition 35 members against rotation upon completion of the evacuation of said one channel, said evacuating means then functioning also to evacuate the other of said channels while said washer and partition members are held against rotation, and spring 40 means in said housing for actuating said evacuating means.

3. A cartridge case of the character described comprising a substantially cylindrical housing including a peripheral wall, a washer arranged for 45 rotation within said housing, spaced relatively inner and outer substantially annular partition members in said housing, said partition members being operatively associated with said washer so as to rotate therewith, said washer and partition 50 members defining a pair of juxtaposed relatively inner and outer channels adapted to receive the cartridges and from which, consecutively, the latter are discharged, the wall of said cylindrical housing being provided with an outlet for said 55 cartridges, means for directing cartridges to said outlet, said cartridges directing means including a fork-shaped cartridge lifter on the inner surface of said wall adjacent said outlet, said lifter extending into the path of the cartridges so that they 60 rise into the outlet as they are pressed against said lifter, means for evacuating one of said channels by rotating said washer and associated partition members and thereby pressing the cartridges of said one channel consecutively against 65 said lifter, and means for holding said washer and partition members against rotation upon completion of the evacuation of said one channel, said evacuating means then functioning also to evacuate the other of said channels while said washer 70 and partition members are held against rotation.

4. A cartridge case of the character described comprising a substantially cylindrical housing including a peripheral wall, a washer arranged for rotation within said housing, spaced relatively 75

inner and outer substantially annular partition members in said housing, said partition members being operatively associated with said washer so as to rotate therewith, said washer and partition members defining a pair of juxtaposed relatively inner and outer channels adapted to receive the cartridges and from which, consecutively, the latter are discharged, the wall of said cylindrical housing being provided with an outlet for said cartridges, means for directing cartridges to said outlet, said cartridge directing means including a fork-shaped cartridge lifter on the inner surface of said wall adjacent said outlet, said lifter comprising a pair of arms extending into the path of the cartridges so that they rise into the outlet as they are pressed against the lifter, one end of the outer partition member terminating adjacent the inner surface of said wall and the other end terminating in a projection of such width as to fit in between the arms of said cartridge lifter when one of said channels is evacuated, means for evacuating said one channel by rotating said washer and associated partition members and thereby pressing the cartridges of said one channel consecutively against said lifter, a shoulder on said wall behind said lifter, said shoulder constituting an abutment against which said projection may bear to stop rotation of said washer and associated partition members, said projection then fitting in between said arms and abutting said shoulder and holding said washer and partition members against rotation, said evacuating means then functioning also to evacuate the other of said channels by pressing the cartridges thereof consecutively against said lifter while said washer and partition members are held against rotation.

5. A cartridge case of the character described comprising a substantially cylindrical housing including a peripheral wall, a washer arranged for rotation within said housing, spaced relatively inner and outer substantially annular partition members in said housing, said partition members being operatively associated with said washer so as to rotate therewith, said washer and partition members defining a pair of juxtaposed relatively inner and outer channels adapted to receive the cartridges and from which, consecutively, the latter are discharged, the wall of said cylindrical housing being provided with an outlet for said cartridges, means on the inner surface of said wall for directing cartridges to said outlet, means for evacuating one of said channels by rotating said washer and associated partition members, means for holding said washer and partition members against rotation upon completion of

the evacuation of said one channel, said evacuating means then functioning also to evacuate the other of said channels while said washer and partition members are held against rotation, said cylindrical housing being provided with a central hollow shaft extending substantially therethrough and about which said washer rotates, a spring-pressed longitudinally displaceable bolt arranged within and having a head extending from said shaft, said cylindrical housing comprising a cover arranged interiorly of said head, and means for locking said cover in place, said means being interposed between said cover and head and being releasable upon outward displacement of said bolt.

6. A cartridge case of the character described comprising a substantially cylindrical housing including a peripheral wall, a washer arranged for rotation within said housing, spaced relatively inner and outer substantially annular partition members in said housing, said partition members being operatively associated with said washer so as to rotate therewith, said washer and partition members defining a pair of juxtaposed relatively inner and outer channels adapted to receive the cartridges and from which, consecutively, the latter are discharged, the wall of said cylindrical housing being provided with an outlet for said cartridges, means on the inner surface of said wall for directing cartridges to said outlet, means for evacuating one of said channels by rotating said washer and associated partition members, means for holding said washer and partition members against rotation upon completion of the evacuation of said one channel, said evacuating means then functioning also to evacuate the other of said channels while said washer and partition members are held against rotation, said cylindrical housing being provided with a central hollow shaft extending substantially therethrough and about which said washer rotates, a spring-pressed longitudinally displaceable bolt arranged within and having a head extending from said shaft, said cylindrical housing comprising a cover arranged interiorly of said head, and means for locking said cover in place, said means being interposed between said cover and head and being releasable upon outward displacement of said bolt, spring means for actuating said evacuating means, a chamber in said housing for said spring means, a cover for said chamber, and oblique cogs on the inner surface of said bolt head, said last-named cover being provided with holes corresponding to and associable with said cogs.

OSKAR ALFRED ÖSTMAN. 55
